UNITED STATES PATENT OFFICE.

ELMER L. DENNIS, OF ROCKFORD, ILLINOIS, ASSIGNOR TO ANDREWS WIRE & IRON WORKS, OF ROCKFORD, ILLINOIS, A CORPORATION OF ILLINOIS.

CARPET-BEATER.

1,078,839.

Specification of Letters Patent. Patented Nov. 18, 1913.

Application filed March 18, 1913. Serial No. 755,160.

To all whom it may concern:

Be it known that I, ELMER L. DENNIS, a citizen of the United States, residing at Rockford, in the county of Winnebago and 5 State of Illinois, have invented certain new and useful Improvements in Carpet-Beaters, of which the following is a specification.

This invention relates to carpet beaters 10 and more particularly to that type of carpet beater having the handle offset from the beater wing; and has for its object an improved construction of such handle and wing embodying novel features in the forming 15 of the handle and beater wing whereby a more efficient, durable and easily manufactured beater is resultant. To accomplish these results I join in a twisted shank, the 20 ends of the strands of wire which form the beater wing, and bend this shank to form a handle support offset from the plane of the shank and beater wing.

A further feature is to lead a fewer number 25 of the strands of wire than that number which constitutes the whole of the handle support, through the forward end of the handle, and to join same with the twisted shank to form a support for said forward end of the handle; and further, to 30 terminate the remaining ends of the strands within the body of the handle in such a manner that said ends are engaged, spaced from each other, in the handle body to hold the handle from turning.

35 In the accompanying drawings: Figure 1 is a view in perspective of my improved carpet beater. Fig. 2 is a longitudinal section through the handle of the beater.

The beater wing 1 may be of any desirable 40 design in which strands of wire are employed to be interwoven to form same. The ends of these strands of wire are converged and twisted or interwoven as at 2 forming a shank, which, it will be seen, lies 45 in the same plane as that of the beater wing. The twisted shank 2 is bent forming an end 3 and again bent back at 4 parallel with the shank 2 forming a support offset from said shank, upon which a handle 5 is 50 mounted. The handle has an opening 6 at its rear end of a size sufficient to allow the twisted strands to enter, the opening extending to a point within the handle sufficient 55 to firmly seat the same therein, and continuing through the handle of a size

sufficient for one or two strands to pass through, having in the drawings illustrated but one strand. This one strand 7 is bent at the point it leaves the front end of the handle and has its end 8 wound about the 60 shank 2, thus forming a support for the forward end of the handle. The remaining ends 9 are terminated within the handle and engaged in the body portion thereof to hold the handle from working loose on its support. These ends may be engaged in the handle thus by various methods, a suitable method being to drive the handle, during the manufacture of the beater, upon the support 4 so as to force the ends 9 into 70 the body portion of the handle, thus fixedly securing the strands therewith.

With this construction a very desirable form of offset handle is obtained, and by forming the strands that are employed in 75 the beater wing into one twisted shank which is bent upon itself to form the offset support, a very rigid construction is resultant. Various numbers of strands may be employed in such a manufactured article, 80 and if necessary, where light wire is used, more than one strand of wire may be employed to pass entirely through the handle to form the front support.

I claim as my invention.

85

1. A carpet beater comprising a beater wing formed of wire, ends of the wire being twisted to form a shank, the shank bent upon itself to form an offset support which is parallelly opposite the shank portion, a 90 handle mounted upon said offset, and one of the ends of said wire extending through the handle and being fastened to the shank body, and a remaining end terminating within the handle body and being fixedly 95 secured therewith.

2. A carpet beater comprising a beater wing formed of intertwined wires, the ends of the wires being twisted to form a shank 100 lying in the same plane with said beater wing, the shank being bent upon itself to form an offset handle-support, a handle mounted upon the handle-support, and one of the wires extending through the handle being bent toward the shank and fastened 105 fixedly thereto, the remaining wire ends terminating within the handle body and being fixedly secured therewith.

3. A carpet beater comprising a beater wing formed of intertwined wires, ends of 110

the wires being joined and twisted into a shank portion, the shank portion being bent upon itself and forming an offset handle-support parallel with the shank portion, a handle having a longitudinal opening extending from its rear end to a point within the handle body, said twisted handle-support located in said opening with certain of its wire ends extending beyond said terminating point of the opening and being fixedly engaged in the handle body, and

means connecting the forward end of the handle and the twisted shank portion to hold said forward end in a fixed relation therewith.

15

In testimony whereof I have hereunto set my hand in presence of two subscribing witnesses.

ELMER L. DENNIS.
